UNITED STATES PATENT OFFICE

ERICH F. JUNGEMANN, OF WOLSEY, SOUTH DAKOTA

PLIER CASE

Application filed April 4, 1929. Serial No. 352,514.

This invention relates to plier cases and more particularly to a plier case for use in securing and housing pliers while disposed in a pocket of a garment, or support from a portion of a garment.

An important object of the invention is the provision in a device of this character of a structure such that the pliers are securely held against possible loss without regard to the position in which the case might be placed, and in which means are provided for ejecting the pliers sufficiently to permit grasping thereof when they are desired for use.

A still further object of the invention is to produce an apparatus of this character in which the pliers are located in position in the case by the insertion thereof.

A further object of the invention is to produce apparatus of this character which may be readily and cheaply manufactured, which will be durable and efficient in surface, and a general improvement in the art.

These and other objects I attain by the construction shown in the accompanying drawings wherein for the purpose of illustration I have shown a preferred embodiment of my invention and wherein:

Figure 1 is a front elevation of a plier case constructed in accordance with my invention;

Figure 2 is a vertical sectional view therethrough;

Figure 3 is a section on line 3—3 of Figure 1;

Figure 4 is a section on line 4—4 of Figure 2;

Figure 5 is a section on line 5—5 of Figure 1;

Figure 6 is a fragmentary rear elevation of the plier case;

Figure 7 is a section on line 7—7 of Figure 6.

Referring now more particularly to the drawings, the numeral 10 indicates a tube rectangular in cross section, and of such dimension that it will readily slidably receive the pliers P with which it is adapted to coact. This tube has the upper portion of its front wall cut away, as indicated at 11, and its upper end open.

The lower end of the tube may likewise be

left open or as illustrated in the present instance, be closed by a perforated wall 12. One side wall 13 of the tube has formed therein a channel 14, preferably produced by pressing the material of the side wall outwardly for a portion of the width of this side wall, and through a predetermined length. This side wall has upper and lower bearings 15 and 16, for the reception of a flat arm 17 hereinafter to be more particularly described. These bearings are preferably produced by striking out from the pressed out portion forming channel 14, transversely extending webs, as more clearly indicated in Figure 2.

Arranged within the lower end of the case is an ejector carriage 18 in the form of a V-shaped yoke, the arms of which are adapted to receive therebetween the nose end of pliers P. One arm of this yoke has an extension forming the arm 17 herein referred to. This extension operates in channel 14 and through bearings 15 and 16.

Between the lower bearing 16 and an outwardly extending stop 19 formed by a struck out portion of the arm 17, a flat sinuous spring 20 extends and this spring constantly tends to raise the carriage 18, and thus cause the handle portions H of the pliers P to project above the upper end of the tube so that they may be readily grasped by the handle. To prevent such extension until it is desired, I mount within the casing a clamping spring 21, at present shown as a leaf secured at 22, to the second side wall and having its terminal portion adapted to engage in the restriction usually produced at the junction of the head and handle portions of the pliers.

To release this spring and thus permit projection of the pliers by the raising carriage, I provide a transversely shiftable member 23 slidably mounted in a channel 23 formed by pressing the front wall of the casing outwardly and then striking inwardly from this pressed out portion a bearing 24, through which the transversely operable member extends. At one end, the transversely operable member has an angular extension 25 projecting through an eye formed on the spring, and at its opposite end has a second angular extension 26 projecting through a slot 27 formed

in the channel base and having a button head 28 for convenient engagement by the finger. By sliding this button transversely the spring 21 is shifted transversely so that the heads of the pliers are permitted to escape thereby, and accordingly the pliers may be lifted by the raising carriage. Other means may obviously be adopted for securing the pliers in position to prevent their elevation by this carriage.

Any suitable means might be employed to secure a case of this character in position upon a support or portion of a garment where its arrangement is desired. In the present instance I have shown the rear wall of the casing as provided at its upper end with spaced eyes 29 and 30, there being two eyes 29 arranged at opposite sides adjacent opposite edges of the wall, and a single eye 30 disposed centrally of this wall. Through these eyes a rod 31 is directed which is surrounded at opposite sides of eye 30 by oppositely wound spring coils 32. Each spring coil 32 has one end thereof abutting the inner face of the rear wall and the opposite ends of these coils are joined by a clamping loop 33 abutting the outer face of the rear wall, this loop preferably being corrugated or otherwise formed to promote grasping.

This loop clamps against the rear wall of the case, the outer wall of a pocket, a belt or other support from which the case should be suspended.

It will be obvious from the foregoing that a device constructed in accordance with my invention, may be very readily and cheaply manufactured, provides a convenient and loss preventing receptacle for pliers, and will be a valuable addition to the art.

It will also be obvious that the construction employed is capable of a very considerable range of change and modification without in any manner departing from the spirit of the invention, and I accordingly do not limit myself to such specific structure except as hereinafter claimed.

I claim:—

1. In a plier case and in combination, a tube having an open upper end permitting insertion of a pair of pliers therein, a spring pressed support for the pliers normally maintaining the pliers partially projected from the case, and releasable means for retaining the pliers in a lowered position within the case against the action of the springs of said support.

2. In a plier case and in combination, a tube having an open upper end permitting insertion of a pair of pliers therein, a spring pressed support for the pliers normally maintaining the pliers partially projected from the case, and releasable means adapted to engage behind the head of a pair of pliers inserted into the case and shifted downwardly therein against the action of said support to

retain the pliers in such depressed position.

3. In a plier case and in combination, a tube having an open upper end permitting insertion of a pair of pliers therein, a spring pressed support for the pliers normally maintaining the pliers partially projected from the case, and a spring secured at one end of the wall of the tube and adapted to engage the pliers behind the head thereof when the pliers have been shifted into the case for a predetermined distance against the action of said support.

4. In a plier case and in combination, a tube having an open upper end permitting insertion of a pair of pliers therein, a spring pressed support for the pliers normally maintaining the pliers partially projected from the case, a spring secured at one end of the wall of the tube and adapted to engage the pliers behind the head thereof when the pliers have been shifted into the case for a predetermined distance against the action of said support, and means operable from the exterior of the case for releasing said spring.

5. In a plier case and in combination, a tube having an open upper end permitting insertion of a pair of pliers therein, a spring pressed support for the pliers normally maintaining the pliers partially projected from the case, releasable means for retaining the pliers in a lowered position within the case against the action of the springs of said support, and means for detachably securing said case to a support.

6. In a plier case, a tube rectangular in cross section, spaced bearings formed in one wall of the tube, a yoke adapted to receive the nose of a pair of pliers having an arm engaged in said bearings, a spring surrounding the arm between one of said bearings and a stop produced on the arm and constantly urging the yoke toward one end of the tube, said end of the tube being open to permit insertion of a pair of pliers therein, and means for retaining the pliers in a predetermined lowered position within the tube against the action of the spring of said yoke.

In testimony whereof I hereunto affix my signature.

ERICH F. JUNGEMANN.
